CIRCUIT INTERRUPTER

Herbert L. Rawlins, Pittsburgh, and James M. Wallace, Braddock, Pa., assignors to Westinghouse Electric Corporation, East Pittsburgh, Pa., a corporation of Pennsylvania

Original application January 16, 1941, Serial No. 374,685, now Patent No. 2,405,606, dated August 13, 1946. Divided and this application November 21, 1944, Serial No. 564,442

12 Claims. (Cl. 200—89)

1

This invention is a division of our copending application Serial No. 374,685 on Circuit Interrupters, filed January 16, 1941, which issued as Patent No. 2,405,606 issued August 13, 1946, and reissued as Reissue Patent No. 23,033 on August 31, 1948, and relates generally to circuit interrupters, and more particularly to circuit breakers and their operating mechanisms.

This invention is especially adapted for use in small reclosing circuit breakers wherein it has certain particular novel cooperation providing certain novel and useful results, however it should be understood that many features of this invention are capable of use with other types of circuit breakers, and even with other types of apparatus.

Automatic reclosing circuit breakers of this type comprise electroresponsive means for causing separation of the breaker contacts to interrupt the circuit, with means for automatically reclosing the breaker contacts following a circuit interrupting operation, and integrating means operative to prevent reclosure of the breaker contacts in response to a predetermined number of closely successive circuit interrupting operations.

One object of this invention is to provide a novel arrangement of biasing means for automatically reclosing a breaker of the type described.

Another object of this invention is to provide novel manual control means for causing opening and closing of the breaker contacts, which control means permits automatic opening of the contacts even when the control is held at its closed circuit position.

Another object of this invention is to provide in an automatic reclosing circuit breaker of the type which is automatically prevented from reclosing in response to a predetermined number of closely successive circuit interrupting operations, novel manually operable means for opening and closing the breaker independent of the automatic opening means, with said manually operable means also being manually movable to render said automatic reclosure-preventing means inoperative following operation of said reclosure-presenting means, so that the breaker may reclose, and said manually operable means further being incapable of preventing automatic opening of said breaker even though held at its closed circuit position.

These and other objects of this invention will become more apparent upon consideration of a detailed description of a preferred embodiment

2

thereof, when taken in connection with the attached drawings, in which

Fig. 1 is a substantially central, longitudinal sectional view of one form of a circuit interrupter embodying the features of this invention.

Fig. 2 is a view similar to Fig. 1, but taken from the opposite side thereof and showing certain of the parts in elevation and with the outer casing removed.

Fig. 3 is a side elevational view of the mechanism shown in Figs. 1 and 2, with a portion of the supporting frame removed.

Fig. 4 is a view like Fig. 3, but illustrating the position of the parts with the breaker contacts locked open, and

Fig. 5 is a partial elevation view of the cover for the interrupter.

Referring to the drawings, the embodiment of the invention illustrated includes a circuit interrupter adapted to be contained in an insulating tubular casing 2, which may be of any desired insulating material, such as porcelain, glass, or the like. The casing 2, as shown in Fig. 1, has a closed bottom end portion and an open top. The open top is provided with an upper terminal cover assembly 4, and the closed bottom of the casing is provided with a lower terminal assembly 6. An intermediate portion of the casing has a substantially cylindrical outer wall portion 8, upon which is mounted a cushioning sleeve 10 of rubber, fiber or the like, and on opposite sides of which may be clamped supporting bracket halves 12 (only one of which is shown) as by bolts 13. The supporting bracket portions 12 are adapted to be extended at one end thereof to support the interrupter in an operative position.

The lower terminal assembly 6 is mounted at the closed bottom portion of the insulating casing 2 by means of a conducting bolt 18, extending through an aperture 19 in the closed end of casing 2, and the bolt is provided with an enlarged disc-like head portion 20 positioned within the casing, with packing material 22 interposed between the head 20 and the adjacent inner surface of the closed end of insulating casing 2. The packing material 22 may be of any desired packing material, preferably one which is resistant to oil, such, for example, as cork, fiber or a synthetic rubber. Bolt 18 has a bore 14 therethrough, the outer end of which is closed by a threaded plug 16 for the purpose of draining casing 2 when desired. The bolt 18 is secured in position by a nut 24 drawn up on

the bolt against a washer 26, positioned between the nut 24 and the outer wall at the closed end of casing 2. A terminal strap 28 having connector elements 31 thereon, may be also secured to the bolt 18 by means of a second nut 30, as shown.

The upper terminal assembly 4 is in the form of a cover for the open end of the casing and, as will be hereinafter more fully explained, also acts to secure the support for the interrupter and operating mechanism in operative relation at the open end of the casing.

Referring to Figs. 3 and 4, it will be noted that the cover 32 is provided with a transversely extending hollow portion for the reception of certain parts of the circuit breaker operating mechanism, and the top wall of this hollow portion is provided with a threaded aperture for the reception of a screw threaded filler plug 34, so that the supply of arc extinguishing fluid within the casing 2 may be renewed when necessary. Cover 32 also includes a peripheral flange portion 36 adapted to seat on the upper end walls of casing 2, and this flange has at its outer edge a downwardly turned lip portion 38, to aid in properly positioning the cover on the open end of casing 2. Packing material 40 is interposed between the cover flange 36 and the open end of the casing, and this material is preferably similar to packing material 22 previously described. Cover 32 is secured to the casing 2 by means of a support 42, fixedly mounted on the outside of casing 2. Support 42 is in the form of an annulus which is substantially channel-shaped in cross-section, with the channel facing the outer surface of casing 2. The annular support 42 is secured to casing 2 by cast metal or the like 44, which is poured in between the support 42 and the outer casing wall, so as to enter within the channel support 42 and between corrugations 46 provided on the outer surface of the casing to securely anchor the support 42 thereto. Cover 32 is preferably secured to support ring 42 by spaced bolts passing through integral outstanding ears (not shown) provided on the cover and supporting ring, respectively. The casing and its terminal assembly thus far described are substantially like that disclosed and claimed in the copending application of J. M. Wallace, Serial No. 345,051, filed July 12, 1940, and issued September 21, 1948 as Patent No. 2,449,867, assigned to the same assignee of this invention.

As stated above, cover 32 is adapted to secure a support for the interrupter and its operating mechanism in operative relation at the open end of casing 2. This support for the interrupter and its operating mechanism (as shown) includes an upper substantially rectangular open frame portion having top and bottom walls 52 and 56, respectively, and side walls 54. Depending from the bottom wall 56 of the upper rectangular frame portion, are a pair of spaced, substantially parallelly extending supporting plate members 58, for supporting the interrupting chamber 62 at the lower ends thereof. The upper rectangular supporting frame portion is provided adjacent the top wall 52 thereof, with oppositely positioned, outwardly extending supporting flanges 60, adapted to be positioned on top of the end wall of casing 2, and be secured in position by screws 62 engaging flanges 48 and an integral lip 50 formed on cover 32.

The interrupting chamber 62, includes a tubular insulating chamber portion 64 formed of any desired insulating material such, for example, as

fiber or the like, which is adapted to have one end thereof threadedly engaged with a threaded socket 60 formed integral with the lower ends of supporting plates 58. The upper wall of socket 60 is provided with a plurality of spaced outlet passages 66, which are controlled by a disc-like valve member 68 mounted within insulating tube 64, and which operates to control the outlet passages 66 in a manner to be hereinafter described. Insulating tube 64 of the interrupter chamber is provided at the other end thereof with an end cap 70, threadedly engaged with the lower end of the insulating tube to close the same. The cap 70 is provided with passages 72 for the flow of fluid into arc chamber 62, and these passages are controlled by a check valve plate 74 adapted to be seated over inlet passages 72, within arc chamber 62. End cap 70 is also provided with a substantially centrally located threaded aperture for the reception of a threaded fixed contact 76.

A movable contact assembly is adapted to cooperate with fixed contact 76, and includes a relatively short contact rod 78 located within interrupting chamber 62, and having an enlarged contact portion 79 with a tapered outer end for engagement with fixed contact 76. Short contact rod 78 is adapted to have the upper end thereof, as viewed in the drawings, threaded into a bore provided centrally of an insulating contact supporting rod 80, which is slidably mounted in a central aperture provided in socket 60. The lower end of insulating contact rod 80 is provided with a counter-bore 82 for receiving a coil compression spring 84, adapted to be seated at the other end thereof on a liquid director member 86. The liquid director 86 is substantially circular in form and includes a base portion 88 having a substantially central aperture for slidably mounting the director on short contact rod 78, for movement between enlarged portion 79 of the contact rod and the lower end of insulating contact rod 80. Coil spring 84 normally biases the liquid director 86 towards the enlarged end 79 of short contact rod 78. However, in the closed position of the contacts, as shown, for example, in Fig. 1, spring 84 will be compressed, so that the liquid director will be located adjacent to the lower end of insulating contact rod 80. The liquid director 86 is provided with passages therethrough for directing the liquid into the path of an arc drawn when the contacts separate, and these include an outlet 90 located adjacent the enlarged contact portion 79, and this opens into a divergent passage 92 in the director, which in turn communicates with a plurality of spaced inlet passages 94, into which liquid contained in the interrupter chamber 62 is adapted to flow when the liquid director is moved upwardly. In the closed position of the contacts, liquid director 86 is adapted to rest on a stop ring 96 secured between a shoulder 98 on end cap 70, and the lower end of insulating tube 64. Valve plate 68 at the upper end of interrupting chamber 62 is provided with an integral angular flange 100 adapted to form a substantially annular groove about the outer surface of insulating contact rod 80, for the reception of packing material 102 to frictionally associate valve plate 68 with insulating contact rod 80.

With the exception of contact supporting rod 80 being of insulating material, the interrupter structure described above is substantially the same as that described in J. M. Wallace Patent No. 2,352,048 on Circuit Interrupters, issued June

20, 1944, to the same assignee of this invention, and which was copending with the aforesaid application of which this is a division. Consequently, for a fuller understanding of the structure and operation of the interrupter, reference is hereby made to the above-mentioned patent. Briefly, the operation of the interrupter 62 is as follows: When contact supporting rod 80 is moved upwardly carrying with it contact rod 78 and contact portion 79, the liquid director 86 is held in engagement with stop ring 96, until the base 88 thereof is engaged by the enlarged contact portion 79, by the biasing action exerted by coil spring 84. However, as soon as the contacts separate an arc will be drawn therebetween causing vaporization of the arc extinguishing fluid which will build up pressure within the interrupting chamber 62. This pressure forces check valve plate 74 to seat on and close off inlet passages 72, and upward movement of contact rod 80 carries valve plate 68 into a closed position with respect to outlet passages 66, to thereby effectively seal the interrupting chamber 62 during the circuit interrupting operation. As soon as the enlarged contact portion 79 on contact support 78 engages wall 88 of the liquid director, the director is moved upwardly along with the contact, and liquid will flow through inlet passages 94 and be directed through outlet passage 90 which will now be positioned as shown in Fig. 4 of the drawings, to direct liquid through the arc path. This lost motion between the contact and liquid director, when the circuit is interrupted, permits easy initial opening movement of the contacts and allow sufficient pressure to build up within the interrupter chamber 62 to close the valve 74, and permits the arc to reach an optimum length before subjecting the same to currents of arc extinguishing liquid. It will be noted that the pressure built up within the interrupter chamber will also act on the relatively large contact supporting rod 80 to assist in moving contact 78 away from fixed contact 76, inasmuch as the supporting rod 80 fits in a piston-like manner in socket 60.

After the circuit is interrupted, the contacts may be reclosed and it will be apparent that as soon as contact supporting rod 80 moves downwardly, it will carry valve plate 68 with it into engagement with the upper edge of insulating tube 64, which is notched as at 61, to permit free outlet of used fluid and any gases which may have been produced by the interrupting operation. At the same time, the head of liquid in insulating casing 2 will cause check valve plate 74 to rise and allow fresh fluid to enter inlet passages 72 to replace the used liquid.

Contact supporting rod 80 is adapted to be actuated by an elongated actuating rod 104 threadedly engaged in a bore in the upper end of rod 80, and having the opposite end secured in a threaded socket in the lower end of a connecting rod 106. The connecting rod 106 has an enlarged portion forming a shoulder 124, and the enlarged portion is adapted to be slidably mounted in a closure plug 119 secured in upper wall 52 of the supporting frame. The upper end of connecting rod 106 is bifurcated for receiving the ends of a pair of toggle links 110 pivotally secured to connecting rod 106 as by a pivot pin 108. The toggle levers 110 are adapted to diverge and have their opposite ends slotted to receive fixed guide pins 112, respectively, mounted on integral supporting lug portions 114 formed on cover 32. A coiled compression spring 116 is adapted to be coiled about each toggle lever 110 to react be-

tween the supporting pins 112 and a shoulder formed on each toggle lever 110 to normally bias actuating rod 104 in a direction to force contact portion 79 into engagement with fixed contact 76.

In order to separate the contacts, a solenoid coil 118 is adapted to be mounted in the rectangular portion of the supporting frame, and the coil is provided with a core 120 adapted to be drawn up into a center bore in the coil. The solenoid core 120 is movably mounted on connecting rod 104, and is provided with a counter-bore portion 122 for receiving therein a coil spring 123. Preferably, the core plug 119 at the upper end of solenoid coil 118 is, like movable core 120, and sides 54 of the supporting frame, of a magnetic material, so as to form a closed magnetic path when plug 119 is engaged by movable core 120.

The solenoid coil 118 is adapted to be connected in series in the circuit through the interrupter, as will be hereinafter described, and upon the occurrence of overload conditions in the circuit, the solenoid coil will attract movable core 120, and move the same upwardly without moving actuating rod 104 or contact 79, until coil spring 123 engages the lower end 105 of connecting rod 106. From this point on, further movement upwardly of movable core 120 will cause compression of spring 123, until the upper end of the core engages shoulder 124 on connecting rod 106 to deliver an impact on connecting rod 106, to separate contact portions 79 and 76, notwithstanding any possible welding of the contacts together. This will cause contact 79 to move upwardly and it is carried for the completion of its stroke after solenoid core 120 engages plug core 119, by the force stored in coil spring 123. Coil spring 123 is preferably of such strength as to overcome the force exerted by toggle springs 116 after a predetermined strain thereof. Moreover, it may be noted that the force exerted by toggle springs 116 in a direction to cause engagement of contact portion 79 with fixed contact 76, will decrease as the contact 79 moves upwardly, because of the toggle effect of levers 110. Moreover, the opening movement of the contacts is further aided by the pressure which may be developed by the arc formed when the contacts separate, acting to move contact 79 upwardly, as described above.

Movable solenoid core 120 is provided adjacent the lower end thereof with oppositely projecting pins 126 having enlarged outer ends for reception in guide slots 128, formed in supporting plates 58, to prevent rotation thereof about a longitudinal axis. A rack 131 is adapted to be pivotally mounted on one of the pins 126 for engagement, in one position of solenoid core 120, with a pinion 130 mounted on a shaft 134 extending between and rotatably mounted in the spaced frame members 58. A spring 132 is adapted to be coiled about guide pin 126, with one end thereof engaging movable core 120, and the other end thereof engageable with rack 131, to normally urge the rack into engagement with pinion 130. It will be noted that the teeth on rack 131 are inclined downwardly so that in the upward motion of the rack with movable core 120, the teeth of the rack will slide freely over the teeth of pinion 130; but on downward motion of the rack the teeth will engage pinion 130 to rotate the same in a clockwise direction as viewed in Figs. 3 and 4. A relatively large gear 138 is also fixed to shaft 134, and this shaft, together with pinion 130 and gear 138, are biased in a counterclockwise direction by a spring 136 coiled about shaft 134, and having one end thereof engageable with

the supporting frame, and the other end thereof engaging a pin 140 on gear 138. The pin 140 projecting from one side of gear 138 is adapted to control a trip controlling member in a manner to be hereinafter further specified.

A short stop lug 142 projects from the opposite side of gear 138 and is normally adapted to engage a lever 144 pivotally mounted on the supporting frame, as by the pivot pin 146, and engageable at the outer end thereof with shaft 134, so that, as viewed in Figs. 3 and 4, the stop pin 142, by its engagement with lever 144, limits movement of gear 138 in a counterclockwise direction under the influence of spring 136. A control lever 150 is preferably pivotally mounted as at 148, on one supporting plate 58, and is provided at one corner of the free end thereof with a curved catch 152, insulatingly secured to control lever 150 in any desired manner, and adapted to be engaged by an adjustable stop lug 154 mounted in the free end of a bimetal element 156. Bimetal element 156 is supported from the frame 58 by an angular bracket 158 and is of conventional construction, that is, it includes a pair of laminations of materials having different coefficients of expansion intimately secured together, with the material having the larger coefficient of expansion comprising the lower lamination, so that upon being heated, the bimetal will deflect upwardly as viewed in the drawings.

It can be seen, therefore, that the lug 154, normally, as shown in Fig. 3, prevents counterclockwise rotation of control lever 150. Clockwise rotation of trip control lever 150 about its pivot 148, is limited by a laterally projecting stop lug 160 integral with the lever, and engageable with an edge of the adjacent supporting plate 58. At the other corner of the free end of control lever 150, there is pivotally mounted as at 162, a contact stop lever 164. This lever, at its upper portion, comprises a pair of legs pivoted on pivot pin 162, at opposite sides of control lever 150, and having laterally extending integral portions 163 connected at their outer ends by an integral stop portion 166, which is engageable with control lever 150 in the position of contact stop lever 164 shown in Fig. 4 of the drawings, to limit relative counterclockwise rotation thereof. One leg of contact stop lever 164, and control lever 150 are provided with lateral extensions 168 and 171, respectively, which are apertured so that the ends of a coiled tension spring 173 may be hooked into these extensions to bias contact stop lever 164, relative to control lever 150, in a counterclockwise direction about pivot point 162. One of the legs of contact stop lever 164 is extended, as shown at 168, so as to be engageable by control pin 140 on gear 138, to normally maintain the contact stop lever in the position shown in Fig. 3 of the drawing, so that the stop portion 167 of the lever is maintained out of the path of movement of pin 126 on solenoid core 120. Gear 138 is adapted to drive a time delay means, comprising pinion 170 with which gear 138 meshes, gear 172 fixed for rotation with pinion 170, and pinion 174 adapted to mesh with gear 172 for driving a paddle wheel 176, positioned below the level of the arc extinguishing liquid within casing 2.

In the operation of the mechanism thus far described, it can be seen that when the contacts are opened by sufficient energization of solenoid coil 118 to draw movable core 120 upwardly into the coil, that even prior to movement of contact 79 by the solenoid, rack 131 will engage pinion 130, irrespective of the amount of

travel of the contact necessary to interrupt the circuit. After interruption occurs, contact 79 is moved into engagement with fixed contact 76 by toggle springs 116. This circuit closing operation will always cause rack 131 to rotate the time delay mechanism a predetermined amount, inasmuch as rack 131 is secured to solenoid core 120 and, therefore, its movement is independent of the amount of separating movement of the contact rod 104 as pointed out above. As the contacts are reclosed following an initial circuit interrupting operation, it will be observed that rack 131 will rotate gear 138 in a clockwise direction as viewed in Figs. 3 and 4 against the bias of spring 136, and this rotation will remove control pin 140 from contact stop lever 164 to permit this lever to be moved by spring 173 in a counterclockwise direction about pivot 162, to a position limited by connecting stop portion 166 and wherein the hook portion 167 of the lever is positioned at a point to intercept pin 126 on solenoid core 120, in the event a closely succeeding interrupting operation occurs. In the event the overload on the circuit has disappeared when the contacts are reclosed, gear 138 will be rotated in a counterclockwise direction by spring 136 slowly, since spring 136 must operate the time delay gearing and paddle wheel 176, until eventually control pin 140 re-engages portion 168 of contact stop lever 164 and moves it back to the position shown in Fig. 3 of the drawings. In this position, it is obvious that in the event an overload again occurs in the circuit, the contacts will be quickly separated by solenoid 118.

In the event, however, that upon reclosure after the first interrupting operation of the circuit breaker, the overload still exists on the circuit, solenoid coil 118 will immediately again lift movable core 120 upwardly, but its movement in this direction is now limited by hook portion 167 of contact stop lever 164, so that its movement will be halted before it is operative to raise contact 79. However, bimetal 156 is connected in series with solenoid coil 118 in the circuit through the interrupter, as will be hereinafter pointed out, and after a predetermined period of time the bimetal becomes heated by the overload current, and deflects to the position shown in Fig. 4, thus releasing catch 152 on control lever 150, so that this lever and stop lever 164 are now free to rotate as a unit about pivot 148 of lever 150, under the biasing force exerted by the solenoid pull through pin 126 on hook portion 167, which pull is exerted along a line offset with respect to pivot 148. This will free the pin 126 and permit the contacts to be opened in the manner previously described. After the circuit is interrupted the contacts will be reclosed by toggle springs 116, with the reclosure again being delayed by operation of the time delay mechanism by rack 131. If the fault has been cleared after the second reclosure, bimetal 156 will gradually assume its normal position shown in Fig. 3 to engage catch 152 on trip control lever 150, and gear 138 will be eventually rotated to the position where control pin 140 removes stop portion 167 of lever 164 from the path of movement of solenoid pin 126, and stop pin 142 engages lever 144. It should be noted that control lever 150 is normally biased to the position shown in Figs. 3 and 4 of the drawings, that is, where stop lug 160 thereof engages the edge of adjacent support plate 58, by a spring 151 coiled about pivot 148 and engaging stop lug 160, and adjacent supporting plate 58.

If the fault has not been cleared by the time the second reclosure is made, the breaker contacts are again quickly separated by solenoid coil 118, and this time there is no time lag before the contacts separate because the bimetal has not had time to cool down, and consequently will remain in the position shown in Fig. 4 of the drawings; and, therefore, levers 164 and 150 may be rotated about pivot 148 by core pin 126 on the upward stroke of the solenoid core.

It can be seen from the foregoing that upon the occurrence of a continuing fault in the circuit, the breaker contacts will be opened a plurality of times, with the first interrupting operation occurring substantially instantaneously in response to the occurrence of the fault, and the second closely succeeding interrupting operation will be delayed a predetermined time depending upon the time necessary to heat bimetal 156. Thereafter, any subsequent interruption will be relatively faster because the time delay means 156 being in a deflected position, will be inoperative to delay any such closely succeeding tripping operation. However, in the event that the fault clears after any reclosure of the breaker contacts, the mechanism will reset so that whenever a continuing fault occurs at a later time, the same sequence of circuit interrupting operations will occur, that is, a first quick opening of the contacts, a second time delay opening, and a quick opening thereafter. In connection with the intermediate time delay opening operation of the breaker contacts, it should be noted that the lost motion connection of the solenoid core with the movable contact, is utilized to prevent separation of the contacts for a time predetermined by bimetal 156. The above described arrangement of successive circuit interrupting operations has the advantage that better coordination with fuses can be obtained when the circuit being protected is subject to surges.

Normally inactive lockout means are provided in association with the mechanism described above adapted to be rendered active for locking the breaker contacts in open circuit position, in response to a predetermined number of closely successive interrupting operations. The lever 144 previously referred to, is adapted to control this lockout means, and it will be noted that this lever is normally biased into engagement with shaft 134, by a spring 178 coiled about pivot 146, and engageable with a lateral extension of the lever and with socket portion 60 of the interrupting chamber. Also pivotally mounted on the lever pivot 146, is a lockout lever 180, which is biased with respect to lever 144, for movement in a counterclockwise direction, by spring 182 also coiled about pivot 146, and having opposite ends thereof engaging lever 144 and lockout lever 180. A lug 181 on lockout lever 180 is engageable with a lateral extension of lever 144 to limit movement of lockout lever 180 relative to lever 144 under the influence of its spring 182.

As previously described, each time the interrupter contacts are closed, rack 131 is operative to rotate pinion 130 and, therefore, gear 138 in a clockwise direction as viewed in Figs. 3 and 4 of the drawings, and after the contacts are reclosed, the gear 138 is then slowly moved back to its normal position shown in Fig. 3. However, in the event of the occurrence of a continuing fault on the circuit, gear 138 will integrate closely successive circuit interrupting operations to finally condition the lockout means described above to prevent further operation of the con-

tacts. In the event of a continuing fault, before gear 138 is restored to its original position following a reclosure of the breaker contacts, these contacts are again reopened and gear 138 upon a second reclosure of the contacts is further advanced a predetermined distance in a clockwise direction by rack 131, to bring stop lug 142 into engagement with the upper edge of lever 144 to move lockout lever 180 into engagement with rod 104 just prior to engagement of the contacts. Now if the fault still remains, the contacts are instantaneously reopened before gear 138 can be moved any substantial distance from its thus advanced position in a counterclockwise direction, at this time shoulder 184 on rod 104 cams lockout lever 180 outwardly in its upward movement so that when a third reclosure is attempted by toggle springs 116, the integral shoulder 184 on rod 104 will engage the lockout lever 180 and prevent reclosure of the circuit breaker contacts. It will be noted that pinion 130 is provided with a solid tooth portion 183 which, when rack 131 attempts to reclose the contacts a third successive time, will be moved to engage and cam rack 131 out of engagement with pinion 130, and thereby permit the rack and solenoid core 120 to drop down under the influence of gravity and spring 123, to the position shown in Figs. 1 and 3. This will obviously permit spring 136 to reset gear 138 into engagement with the inclined end of lever 144. However, lockout lever 180 is maintained in the position shown in Fig. 4 to lock the contacts open by reason of its frictional engagement with shoulder 184.

To reset the breaker, that is, to place it in service again following an automatic lockout operation, it is necessary to raise the moving contact in order to release lockout lever 180 and permit spring 178 to move the lever 144, and, consequently, lockout lever 180 away from rod 104 and thus release the movable contact and permit the same to be reclosed by toggle springs 116.

The movable contact may be manually lifted by means of a lever 186 secured to a shaft 187 extending transversely across the hollow portion of cover 32, with one end thereof extended outside of the hollow portion of the cover to have secured thereto an operating crank 190. The crank 190 has an enlarged aperture 192 at the outer end thereof, for the reception of a hook stick operating member or the like. It will be noted that operating crank lever 186 is provided with a curved inner end 188, positioned at one side of toggle levers 110 and beneath toggle pivot pin 108, so that although connecting rod 104 and movable contact 79 may be raised by lever 186 manually, it cannot be moved into engagement with the fixed contact 76 by this lever, and consequently it is obvious that the breaker contacts are trip free of manually operable lever 190 inasmuch as they may be automatically opened by the current responsive tripping means, independent of operation of the manual control lever 190.

As in the patent to H. L. Rawlins et al., No. 2,318,421 on Circuit Interrupter, issued May 4, 1943, to the same assignee of this invention, and copending with the aforementioned application 70 of which this is a division, the cover 32 may be provided with a manually operable locking means for maintaining the breaker contacts in an open circuit position when desired, as by a locking lever 210 pivotally mounted on the outside of the cover as at 212 and normally resting on a sup-

porting rib 214 integral with the cover at the outside thereof (Figs. 2 and 5). Operating crank 190 is provided with an integral stop shoulder 218 positioned so as to be engageable with locking lever 210 when the latter is manually rotated counterclockwise as viewed in Fig. 5, and when the operating crank is in its lower position corresponding to the open circuit position of the contacts. The cover may also be provided with a sight glass 194, as in the aforesaid copending application, for observation of a rod 198 mounted on a float 198, to render the level of arc extinguishing fluid readily visible from the exterior of the interrupter. Likewise, the cover may embody a terminal 200 for connection of a circuit conductor thereto.

The electrical circuit through the breaker may be traced from the lower terminal 34, conducting strip 28 to bolt 18, its enlarged head 20, through coiled compression spring 75 engageable between the enlarged head 20 of bolt 18 and end cap 70 of interrupter chamber 62, through fixed contact 76 and contact rod 78. The insulating contact rod support 80 is provided with an off center bore 204 for receiving a flexible conductor 202, which is connected to contact rod 78 as at 206, and this flexible conductor is directed upwardly to be connected to one end of solenoid coil 118. The other end of solenoid coil 118 is connected by a flexible conductor 207, to the free end of bimetal 156, and since the bimetal is supported on frame supporting plate 58, the circuit proceeds from the bimetal through the frame to cap 32 and terminal 200. It can be seen, as previously referred to, that the coil 118 and bimetal 156 are thereby arranged in series circuit relation so as to be effective to interrupt the circuit in the manner described above.

From the foregoing, it can be seen that the circuit breaker constituting this invention is capable of giving a relatively quick or an instantaneous trip when an overload first occurs on the circuit, and in the event the overload continues after automatic reclosure of the breaker contacts, a second time lag tripping will occur, and thereafter in the event the fault continues the subsequent tripping will be a quick or instantaneous one, and thereafter the breaker contacts will be locked in an open circuit position. It will also be noted that the time delay means operative to delay a reclosure of the breaker contacts is dependent upon the viscosity of the arc extinguishing fluid, so that the time delay in reclosing the breaker contacts will correspond to the time necessary for flushing the interrupting chamber so as to always insure a good flushing action and replacement of used arc extinguishing liquid in the interrupting chamber 62, with fresh liquid. Another important feature is that this time delay in reclosure of the breaker contacts will be a constant value for any given viscosity of arc extinguishing fluid, due to the fact that the time delay is controlled by movement of the solenoid core, rather than by movement of the contacts, and because of the lost motion between the core and movable contact, the movement of the core will always be sufficient to engage rack 131 with the time delay reclosing means on each interrupting operation of the breaker. Also novel means have been disclosed for locking the breaker contacts in an open circuit position in response to a predetermined number of closely successive interrupting operations, but which will be inoperative to lock the breaker contacts

open irrespective of the number of non-successive interrupting operations of the breaker.

Having described a preferred embodiment of the invention in accordance with the patent statutes, it is desired that the invention be not limited to this particular embodiment inasmuch as it will be obvious particularly to persons skilled in the art that many modifications may be made in this particular structure and still remain within the scope of this invention.

We claim as our invention:

1. In a circuit interrupter, separable contacts, means for separating said contacts in response to a predetermined circuit condition to interrupt the circuit, said contacts being biased closed to automatically close the circuit after a circuit interrupting operation, an actuating member adapted to be advanced a predetermined amount during each separation and reclosure cycle of said contacts and to slowly return to a normal position, movably mounted spring biased means normally positioned to be engaged and moved by said member in response to predetermined advancement thereof to another position where it prevents reclosure of said contacts, manually operable means for rendering said reclosure preventing means inoperative, to thereby permit reclosure of said contacts, said manually operable means adapted to occupy one position when said contacts are closed and being movable to a second position to cause opening of said contacts, and said manually operable means being free of said contacts when at said one position so that said contacts may be separated by said electro-responsive means even when said manually operable means is held at said one position.
2. In an automatic circuit recloser, separable contacts, overload-responsive means for causing separation of said contacts to interrupt the circuit, means for automatically reclosing said contacts after a circuit interrupting operation, normally inactive means adapted when activated to prevent reclosure of said contacts by said reclosing means, integrating means biased to a normal position and adapted to be advanced a predetermined amount on each circuit interrupting operation, said integrating means mounted for movement independent of said normally inactive means and arranged so that when advanced an amount greater than said predetermined amount by a plurality of closely successive circuit interrupting operations it will activate said reclosure-preventing means, the return movement of said integrating means under the influence of its bias being independent of said reclosure preventing means, and manually operable means for causing resetting of said reclosure-preventing means.
3. In an automatic circuit recloser, separable contacts, overload-responsive means for causing separation of said contacts to interrupt the circuit, means for automatically reclosing said contacts after a circuit interrupting operation, normally inactive means adapted when activated to prevent reclosure of said contacts by said reclosing means, integrating means responsive only to a predetermined number of closely successive circuit interrupting operations to be advanced a predetermined amount, means positioned to be engaged by said integrating means only when advanced said predetermined amount to activate said reclosure-preventing means, and manually operable means mounted for movement independently of said integrating means for resetting said reclosure-preventing means.
4. In a circuit interrupter, separable contacts,

means for separating said contacts in response to a predetermined circuit condition, means for automatically closing said contacts in response to a circuit interrupting operation, means for delaying closing movement of said contacts including an actuating member adapted to be advanced a predetermined amount by each operation of said reclosing means, movably mounted latch means normally occupying a released position for releasably holding said contacts separated when moved to latching position, and said latch means having a part positioned to be engaged by said actuating member after it has been advanced a predetermined amount to move said latch means to its latching position.

5. In a circuit interrupter, separable contacts, means for separating said contacts in response to a predetermined circuit condition, means for automatically closing said contacts in response to a circuit interrupting operation, means for delaying closing movement of said contacts including an actuating member adapted to be advanced a predetermined amount by each operation of said reclosing means, normally inactive means for releasably holding said contacts separated when activated, said last mentioned means having a part positioned to be engaged by said actuating member after it has been advanced a predetermined amount to activate said holding means, and means for slowly returning said actuating member to its original position independent of said holding means, whereby said contact holding means is operative to maintain said contacts separated only in response to a predetermined number of closely successive circuit interrupting operations, and said actuating member will be reset while the contacts are maintained separated.

6. In a circuit interrupter, separable contacts, means for separating said contacts in response to a predetermined circuit condition, means for automatically closing said contacts in response to a circuit interrupting operation, means for delaying closing movement of said contacts including an actuating member adapted to be advanced a predetermined amount by each operation of said reclosing means, movably mounted latch means normally occupying a released position for releasably holding said contacts separated when moved to latching position, said latch means having a part positioned to be engaged by said actuating member after it has been advanced a predetermined amount to move said latch means to its latching position, and manually operable means for releasing said latch means.

7. In a circuit interrupter, separable contacts, means for separating said contacts in response to a predetermined circuit condition, means for automatically closing said contacts in response to a circuit interrupting operation, means for delaying closing movement of said contacts including an actuating member adapted to be advanced a predetermined amount by each operation of said reclosing means, movably mounted latch means biased to a normal inoperative position for releasably holding said contacts separated when rendered operative, said latch means being positioned to be engaged by said actuating member after it has been advanced a predetermined amount to render said latch means operative, and manually operable means for actuating said contacts in a direction to release said latch means and permit the latter to resume its normal inoperative position under the influence of its bias.

8. In a circuit interrupter, separable contacts,

means for separating said contacts in response to a predetermined circuit condition, means for automatically closing said contacts in response to a circuit interrupting operation, means for delaying closing movement of said contacts including an actuating member adapted to be advanced a predetermined amount by each operation of said reclosing means, movably mounted latch means biased to a normal inoperative position for releasably holding said contacts separated when rendered operative, said latch means being positioned to be engaged by said actuating member after it has been advanced a predetermined amount to render said latch means operative, 10 manually operable means for actuating said contacts in a direction to release said latch means and permit the latter to resume its normal inoperative position under the influence of its bias, and means biasing said actuating member in a direction to reset independently of said latch means.

9. In a circuit interrupter, separable contacts, means for separating said contacts in response to a predetermined circuit condition, means for automatically closing said contacts in response to a circuit interrupting operation, means for delaying closing movement of said contacts including an actuating member adapted to be advanced a predetermined amount by each operation of said reclosing means, means having a movably mounted part positioned to be engaged by said actuating member after it has been advanced an amount greater than said predetermined amount to move said part to a position where reclosing 30 of said contacts is prevented, and manually operable means for effecting release movement of said reclosure-preventing means.

10. In a circuit interrupter, separable contacts, means for separating said contacts in response to a predetermined circuit condition, means for automatically closing said contacts in response to a circuit interrupting operation, means for delaying closing movement of said contacts including an actuating member adapted to be advanced a predetermined amount by each operation of said reclosing means, movably mounted means adapted at one position thereof to prevent reclosing of said contacts but normally at another position where it does not interfere with contact closing, said movably mounted means having a part positioned to be engaged by said actuating member only in response to advancement of the latter an amount greater than said predetermined amount to move said movable means to its aforesaid one position and thus prevent reclosing of the contacts.

11. In a circuit interrupter, separable contacts, means having a part movable a predetermined amount from a normal position for separating said contacts in response to a predetermined circuit condition, means for automatically closing said contacts in response to a circuit interrupting operation, means for delaying closing movement of said contacts including an actuating member adapted to be advanced a predetermined amount by each operation of said reclosing means, movably mounted latch means normally occupying a released position for releasably holding said contacts separated when moved to latching position, said latch means having a part positioned to be engaged by said actuating member after it has been advanced a predetermined amount to move said latch means to its latching position, manually operable means for releasing said latch means, 70 stationary stop means separate from and inde-

15

pendent of said contact means for defining the normal position of said part, and means for restoring said part to its normal position after a circuit interrupting operation.

12. An automatic reclosing circuit breaker comprising, separable butt-type contact means one of which is mounted on a slideable contact rod for movement into and out of engagement with the other, overload-responsive means having a part slidably mounted on said rod and having lost motion therewith so as to be movable a predetermined distance from a normal position in response to overloads before causing separation of said contacts, means for automatically closing said contacts in response to a circuit interrupting operation, means for delaying closing movement of said contacts including an actuating member adapted to be advanced a predetermined amount by each operation of said reclosing means, movably mounted latch means normally occupying a released position for releasably holding said contacts separated when moved to latching position, said latch means having a part positioned to be

16

engaged by said actuating member after it has been advanced a predetermined amount to move said latch means to its latching position, manually operable means for releasing said latch means, stationary stop means separate from and independent of said contact means for defining the normal position of said part, and means for restoring said part to its normal position after a circuit interrupting operation.
